(57) **CLAIM**

The ornamental design for a plank installation tool, as shown and described.

DESCRIPTION

FIG. 1 is a front perspective view of a plank installation tool, showing our new design in use with a plank;

FIG. 2 is a front perspective view thereof, illustrated with the plank omitted;

FIG. 3 is a front elevational view of FIG. 2;

FIG. 4 is a rear elevational view of FIG. 2;

FIG. 5 is a left-side elevational view of FIG. 2, the right-side elevational view being a mirror image thereof;

FIG. 6 is a top plan view of FIG. 2; and,

FIG. 7 is a bottom plan view of FIG. 2.

The broken lines illustrating planks in FIGS. 1 depicts environmental matter that forms no part of the claimed design. The remaining broken lines in the figures depict portions of the plank installation tool that form no part of the claimed design.

1 Claim, 4 Drawing Sheets
